DESIGN FOR A FLASHLIGHT

Charles S. Packer, Chicago, Ill., assignor to Just-rite Manufacturing Company, Chicago, Ill., a corporation of Illinois

Application October 18, 1943, Serial No. 111,415

Term of patent 14 years

To all whom it may concern:

Be it known that I, Charles S. Packer, a citizen of the United States, residing at Chicago, in the county of Cook and State of Illinois, have invented a new, original, and ornamental Design for a Flashlight, of which the following is a specification, reference being had to the accompanying drawings, forming part thereof.

In the drawings—

Figure 1 is a front elevational view of a flash-
light showing my new design;

Figure 2 is an elevational view of the right side of the flashlight as shown in Figure 1;

Figure 4 is an elevational view of the left side
of the flashlight; and

Figure 5 is a rear elevational view.

I claim:

The ornamental design for a flashlight, as shown.

CHARLES S. PACKER.
